Primary Examiner—Bernard Ansher*Assistant Examiner*—C. Tuttle*Attorney, Agent, or Firm*—Thomas R. Lampe**[57] CLAIM**

The ornamental design for a holder for an electric, hand held hair dryer, as shown and described.

DESCRIPTION

FIG. 1 is a front perspective view showing my new design, the broken line showing of the hair dryer being for illustration purposes and forming no part of the claimed design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof; and,

FIG. 7 is a bottom plan view thereof.

FIG. 5

FIG. 3

FIG. 1

FIG. 4

FIG. 7
